Primary Examiner—Susan J. Lucas*Assistant Examiner*—Cynthia E. Ramirez*Attorney, Agent, or Firm*—Greenblum & Bernstein, P.L.C.[57] **CLAIM**

I claim the ornamental design for a base of steam generator for iron, as shown and described.

DESCRIPTION

FIG. 1 is a perspective view from the front and from the right of my new design;

FIG. 2 is front elevation view thereof;

FIG. 3 is a rear elevation view thereof;

FIG. 4 is a right side elevation view thereof;

FIG. 5 is a left side elevation view thereof;

FIG. 6 is a top view thereof; and,

FIG. 7 is a bottom view thereof.
